UNITED STATES PATENT OFFICE

WILLIAM RODERICK BARCLAY AND WILLIAM THOMAS BUCKINGHAM ROBERTS, OF LEICESTER, ENGLAND, ASSIGNEES TO UNITED SHOE MACHINERY CORPORATION, OF PATERSON, NEW JERSEY, A CORPORATION OF NEW JERSEY

FASTENER-INSERTING MECHANISM

Application filed July 23, 1927, Serial No. 208,009, and in Great Britain September 3, 1926.

This invention relates to fastener-inserting mechanisms and is particularly concerned with the driving of heel-attaching nails in the manufacture of shoes, especially where the heels are to be attached from inside the 5 shoes and are of the Louis type.

In attaching such a heel, it is desirable that the nails shall enter as closely as possible to the edge of the heel to obtain a tight rand-crease. At the same time, the points of the 10 nails must not pass through the side walls of the heel. The present invention has for one of its objects the attainment of these results. This is accomplished by providing 15 novel means for causing such heel-attaching nails, as they are being driven, to be bent or curved, preferably toward each other and toward the center of the heel. Simultaneously with this, an attaching nail may, if desired, be driven into the heel along a recti- 20 linear path.

The above and other objects and the features of the present invention will become evident from a consideration of the following 25 purely illustrative description and accompanying drawings of a particular form of nail-driving mechanism according to the invention.

In the drawings,

30 Fig. 1 is a section on the line I—I of Fig. 2, showing one form of our improved nail-driving mechanism;

Fig. 2 is a plan view of said mechanism; and

35 Fig. 3 is a side elevation of the upper portion of the mechanism.

This nail-driving mechanism comprises a post 1 of a work-supporting jack adapted for use in a heel-attaching machine of the character described, for example, in Letters Patent of the United States No. 1,545,575, Stan-dish, July 14, 1925. The post has slidingly mounted in it a vertically movable plunger 2, which is urged downwardly by a compres-sion-spring 3 located in a recess formed in the plunger, and which bears against the bottom of said recess and against a screw 4 threaded into the post and projecting into the recess. The plunger 2, at its upper end, is 45 provided with a circular head 5, to the top

face of which is fixed a circular plate 6 hav-ing spaced from one another, near its edge, five openings, which are recessed on the under side of the plate. Each opening in the plate receives a nail-driver 7, the head of which enters the corresponding recess and is 55 supported by the upper face of the head of the plunger. The head of each driver, where it rests upon the plunger-head, is rounded, and the recesses in the plate are somewhat larger than the drivers, so the latter are free to swing about their lower ends slightly in any direction from a vertical position. The upper ends of this series of outer drivers are 60 guided in vertical spaces between the side walls of a series of five blocks 8, which are fixed in the upper end of a tube 9 enclosing the drivers, the lower end of the tube being secured to the post 1. At the top of the tube is a nail-bending ring 10, the upper inner 65 edge of which has an inwardly extending flange, with its under face 11 beveled upwardly and inwardly at an angle, which is shown as about forty-five degrees. The top edges of the five blocks are beveled to fit 70 against the flange.

Pivoted on horizontal pins 12 at the lower ends of the blocks are driver-passage-forming and nail-bending fingers 13, which extend upwardly in each space between the blocks nearly to their tops on the inner side of the drivers. These fingers are all urged inwardly toward each other by a coil-spring 14 sur-rounding the fingers, just above their pivots, and retained in a groove 15 extending about the blocks. The outer faces of the fingers 13, which are grooved vertically, the sides of the spaces between the blocks 8, and the inner faces of the tube 9 and ring 10 furnish driver-passages. These passages, at their upper ends, are overhung or partly closed by the beveled lower face 11 on the ring 10, forming constricted nail-bending outlet portions, this unitary member or ring 10 being common 80 to all the passages. The upper ends of the driver-passages are opened to receive the nails when the fingers are swung inwardly by the spring 14. Slidably mounted at the center of the blocks and in the plunger 2 is a vertical finger-controlling tube 16 having 85

fixed to its lower end a block 17. This block is movable in a recess in the plunger 2 and, during the descent of said plunger, is engaged by the upper wall of the recess to shift the tube downwardly. During the elevation of the plunger, the tube 16 is moved with it by the engagement of a screw 18, vertically adjustable at the bottom of the recess, with the lower end of the tube. The tube at its upper end has a head 19, which, at its under side, is beveled downwardly to join the tube. The head 19 engages projections 20 on the fingers 13, so that, during reciprocation of the tube under the influence of the plunger, the fingers are swung out upon their pivots to narrow the outlet-openings, to be returned by the spring 14 when the head leaves the projections.

The tube 16 may have slidingly mounted within it, near the vertical axis of the jack, a driver 21, which, at its lower end, rests on the head of the screw 18. The bore in the tube, at its upper end, is enlarged to receive a nail-guiding tube 22. The latter has at its upper extremity a thin head 23, which rests on the tops of the blocks 8 and is held in position by a circular plate 24 having a central beveled opening to engage the beveled edge of the head 23. The plate 24 has also a beveled outer edge, over which extends the beveled flange of the nail-bending ring 10. The plate is provided with five slots 25 extending inwardly from its edge to permit the passage of nails, a pin 26 in the plate entering a hole in the top of one of the blocks to position the slots over the nail-passages.

The nail-bending ring 10 has a flange 27, which is engaged by a flange 28 overhanging the bore of a shoe-supporting block or jack-top 29. This block is fixed to the tube 9 by conical-pointed screws 30, which enter conical holes in the side of the tube. The screws and holes are so arranged that, when the screws are turned inwardly, the shoe-supporting block 29 is drawn down to clamp the ring 10 between the flange 28 on the block and the top of the tube 9. The shoe-supporting block 29 has at each side a slot, which exposes a portion of the outer face of the flange 27 on the ring. In this face are formed a number of vertical grooves 32, so that, when the ring is loosened by slackening the clamping screws 30, a tool may be inserted through one or the other of the slots into engagement with a groove in the flange, and the ring may thereby be rotated to bring fresh wearing portions of the surface of its flange into position for bending the nails.

In operation, the heel-attaching machine stops at a point in its cycle when the plunger 2 is descending and the head 19 of the finger-controlling tube 16 is still above the projections 20 on the fingers 13, so the fingers are swung in toward each other by the spring 14, and the upper ends of the outer driver-pas-

sages are therefore open. Heel-attaching nails are at this time inserted heads down in the desired driver-passages, either by hand or by a suitable loading mechanism. Then a shoe and a heel to be attached are positioned on the block 29, and the machine is started. The plunger first moves down, and, by engagement with the block 17, the head of the finger-controlling tube 16 is brought into contact with the projections on the fingers to spread these out and hold them positively in this position. The upper ends of the outer driver-passages are thus so contracted that there is just room for the shanks of the nails to pass out between the upper ends of the fingers and the face 11 on the flange of the bending ring. The plunger 2 is now moved up, and, during the greater part of this travel, the finger-controlling tube 16 is stationary; owing to the space between the lower end of said tube and the screw 18 in the plunger, and the outlet-openings of the driver-passages remain nearly closed. During the upward movement of the plunger, the nails are driven into the shoe, and, because of the inwardly inclined constricted passages between the ring and the upper ends of the fingers the outer nails are all positively bent, their form being changed before their points emerge from the passages, and follow curved paths toward each other and toward the longitudinal axis of the post. Just before the plunger reaches the top of its stroke, the screw 18 engages the bottom of the finger-controlling tube 16, and, during the last part of the upward movement of the plunger, the tube is raised, and its head 19 lifted above the projections 20 on the fingers. This allows the spring 14 to swing the fingers in to open the driver-passages, so that interference with the heads of the nails is avoided. The upper ends of the drivers, during the last part of their elevation, engage the face 11 and swing slightly about their lower ends. The plunger 2 then descends to its stopping position, leaving the tube 16 raised and the driver-passages open to receive the succeeding load of nails. The center nail is driven into the heel at the same time as the outer nails, following a rectilinear path. If it is not desired to drive a center nail, it is only necessary to withdraw the driver 21, which may readily be lifted out of its guide and will then not mark the shoe.

Having described our invention, what we claim as new and desire to secure by Letters Patent of the United States is:

1. In a fastener-inserting mechanism, fastener-driving means, a movable member furnishing a wall of a passage for the driving means at the point of emergence of the fasteners from said passage, and means acting during the movement of the driving means for changing the position of the member.
2. In a fastener-inserting mechanism, fas-

tener-driving means, a movable member arranged to bend a fastener while it is being driven and before its contact with the work, and a controlling member for the bending member movable by the driving means.

5 3. In a fastener-inserting mechanism, fastener-driving means, a movable member furnishing a portion of a fastener-bending passage, and a controlling member for the member first mentioned into contact with which

10 controlling member the driving means moves near its extremes of travel.

4. In a fastener-inserting mechanism, fastener-driving means, a movable member arranged to bend a fastener, means arranged to normally hold the member out of bending position, means operable with the fastener-driving means for releasing the bending member from the holding means, and means for moving the member into bending position.

5. The combination with a work-support having a passage, of a fastener-driver movable therein, a normally fixed member having an inclined surface overhanging the outlet of the passage, and a member movable toward and from the inclined surface and furnishing the opposite side of the passage.

6. The combination with a work-support having a passage, of a fastener-driver movable therein, a normally fixed member having an inclined surface overhanging the outlet of the passage, a member movable toward and from the inclined surface and furnishing the opposite side of the passage, and means movable with the driver for moving the passage-forming member.

7. The combination with a work-support having a passage, of a fastener-driver movable therein, a movable member furnishing one side of the passage, and a member movable under the influence of the driver and contacting with the passage-forming member to change the width of the passage during the insertion of fasteners.

8. The combination with a work-support having passages, of a nail-bending finger pivoted at one side of each passage, a plunger carrying drivers operating in the passages, and a sleeve movable by the plunger and contacting with the fingers.

9. The combination with a work-support having passages, of a nail-bending finger pivoted at the inner side of each passage, a spring acting upon the fingers and tending to draw them together, a plunger carrying drivers operating in the passages, and a sleeve movable by the plunger and contacting with the fingers to separate them.

60 10. The combination with a work-support having passages, of a nail-bending finger pivoted at one side of each passage, a bending ring having an inclined surface overhanging the ends of the fingers, a plunger carrying drivers operating in the passages,

and a sleeve movable by the plunger and contacting with the fingers.

11. In combination, a jack having a series of nail-receiving passages, a driver movable in each passage, and means arranged to change the form of the nails by bending them toward the longitudinal axis of the jack while they are being driven and before their leading extremities emerge from the passages.

12. A jack having a series of nail-receiving passages with constricted outlet-openings, a driver movable in each passage, and means arranged to increase the width of the outlet-openings as the drivers approach them.

13. A jack having a series of nail-receiving passages with constricted outlet-openings, a driver movable in each passage, and means arranged to increase the width of the outlet-openings as the drivers approach them and to maintain said increased width after the completion of the driving stroke.

14. A jack having a series of nail-receiving passages with constricted outlet-openings, a driver movable in each passage, and a member movable with the drivers and arranged to control the width of the outlet-openings.

15. In combination, a jack provided with an opening, a bending ring surrounding the opening, movable members cooperating with the ring to form nail-receiving passages, and drivers operating in the passages.

16. In combination, a jack provided with an opening, a bending ring surrounding the opening, movable members cooperating with the ring to form nail-receiving passages, drivers operating in the passages, and means for moving the members under the influence of the drivers.

17. In combination, a jack having an opening, a bending ring surrounding the opening and furnishing a portion of nail-bending passages, and retaining means for the ring organized to permit said ring to be rotated to present fresh wearing surfaces to the passages.

18. In combination, a jack, a jack-top carried thereby, a nail-bending member with which the top contacts, and means arranged to draw the top into clamping engagement with the bending member or to release said member for adjustment.

19. In combination, a jack, a series of drivers operating therein, and means associated with certain of the drivers for causing driven fasteners to follow curved paths, one of the drivers being arranged to insert its fastener along a rectilinear path.

20. In combination, a jack, a driver situated in proximity to the axis of the jack, a series of drivers surrounding the axial driver, and a bending device associated with each of the surrounding drivers and arranged to deflect nails driven, toward the axis of the jack.

21. In a machine for inserting headed

fasteners, a work-support having a fastener-receiving passage, fastener-driving means operating in the passage, fastener-bending means associated with the passage, and means for increasing the width of the passage as the head of the fastener approaches the bending means.

5 In testimony whereof we have signed our names to this specification.
